BUILDING STRUCTURE

Peter Butten and Walter Butten, Osakis, Minn.

Application June 25, 1936, Serial No. 87,185

14 Claims. (Cl. 108—32)

This invention, while it relates particularly to roofs for silos, tanks, barns and other buildings, also has application to walls, partitions and panels of many different types.

It is the general object of the invention to provide a novel and improved building structure which is particularly applicable to be used as a roof for a silo or the like, and which can be erected with great ease and with little expense to effectively form a water proof closure having great strength and rigidity.

A further object is to provide a roof or wall-like structure including ribs in the nature of rafters or studs and spanner sheets disposed between and bridging the space between adjacent ribs, there being provision made for permitting variance in the space between adjacent ribs as the structure is being erected to meet the requirements of the silo or other building in connection with which the structure of the invention is used.

More specifically it is an object of the invention to provide a novel and improved silo roof of light, strong and cheap construction which although constructed of building units of a standard type, as the roof is erected, can be adjusted to fit the particular silo in connection with which it is used in case the silo should be somewhat out of round, or in case there should be some variance from normal in the size of the upper portion of the silo to which the roof is applied.

The objects and advantages of the invention will more fully appear from the following description, made in connection with the accompanying drawings, wherein a silo roof embodying the invention is first illustrated and wherein like reference characters refer to the same or similar parts throughout the various views and, in which,

Fig. 1 is a perspective view illustrating the upper portion of a silo with a roof embodying the invention;

Fig. 2 is a vertical section taken through the silo roof on the line 2—2 of Fig. 1, as indicated by the arrows;

Fig. 3 is a horizontal section taken on the line 3—3 of Fig. 1, as indicated by the arrows;

Fig. 4 is a horizontal section taken as on the line 4—4 of Fig. 1, as indicated by the arrows;

Fig. 5 is a vertical section taken on the line 5—5 of Fig. 1, as indicated by the arrows;

Fig. 6 is a horizontal section taken on the line 6—6 of Fig. 1, as indicated by the arrows;

Fig. 7 is a view in side elevation on a reduced scale of one of the ribs shown in Figs. 1 to 6;

Fig. 8 is a perspective view illustrating one of the spanner sheets shown in Figs. 1 to 6;

Fig. 9 is a view in side elevation illustrating one of the clamping bars that is used in the construction shown in Figs. 1 to 6;

Fig. 10 is a view in front elevation illustrating a portion of a wall that may be constructed in accordance with the present invention;

Fig. 11 is a perspective view illustrating one of the ribs that may be used in the wall shown in Fig. 10;

Fig. 12 is a perspective view illustrating one of the spanner sheets that may be used in the wall shown in Fig. 10; and

Fig. 13 is a perspective view illustrating one of the clamping bars that may be used in the wall shown in Fig. 10.

Referring first to the embodiment of the invention, shown in Figs. 1 to 9 of the drawings, portions of a silo are shown including a circular wall 14 formed by a multiplicity of staves, a chute 15 and hoop 16 encircling the upper part of the wall 14 immediately below the upper edge thereof, the ends of the hoop being carried through a block 17 and having nuts 18 attached thereto which bear against the ends of the block to tighten the hoop.

The silo roof is formed by connecting together a number of separate structural units, these units including long ribs 19 having the function of studs or rafters, spanner sheets 20 and 21 respectively, and clamping bars 22.

The ribs 19 for use in producing the curved roof shown are of arcuate construction and the lower ends of these ribs are located in circumferentially spaced relation at the outer side of the silo wall just below the top thereof. The upper ends of these ribs are secured to a ring 23 which forms an opening at the top of the silo roof. Ribs 19 are of channel-shape in cross section.

Each spanner sheet 20 is equipped with outwardly turned side flanges 20a and it tapers from its lower end toward its upper end. The spanner sheets 20 are made of light gauge sheet material and accordingly these sheets may be curved to

arcuate form as the roof structure is erected; therefore, as originally made, it will not be necessary to give them an arcuate curvature. Each spanner sheet 20 is used to span the space between a pair of adjacent ribs 19 and, as best shown in Fig. 3, the sheets are so located relative to the ribs that the flanges 20a are received within the channels of the ribs.

Preferably only one or at the most two of the spanner sheets 21 will be used in the erection

of an ordinary silo roof, although of course it will be possible to use the spanner sheets 21 to the exclusion of the spanner sheets 20 and in substitution therefor in erecting the roof. In 5 many instances, when the spanner sheets 20 are used, it will be unnecessary to use any of the spanner sheets 21. Spanner sheets 21, like the spanner sheets 20, are made of light gauge material and taper from their lower ends upwardly. 10 The sheets 21 are preferably of somewhat greater width than the spanner sheets 20 and unlike the sheets 20 they are equipped with side flanges 21a at one edge only. As best illustrated in Fig. 4, a spanner sheet 21 when used is located to span 15 the space between a pair of adjacent ribs 19 in such manner that the flange 21a of the sheet is received within the channel of one of the ribs 19, while the opposite edge portion of the spanner sheet completely overlaps the adjacent rib 19 to 20 be received immediately below a portion of the next adjacent spanner sheet 20 or 21 as the case may be.

The clamping bars 22 are of substantially W-shape in cross section so as to each form a pair of 25 adjacent channels of V-shape in cross section on their outer surfaces and to form on their lower surfaces a central channel of inverted V-shape. The bars 22 are of the same length as are the ribs 19 and like the ribs they are made of arcuate 30 formation as shown in Fig. 9, for use in a round roof such as that shown in Fig. 1. The clamping bars 22, as best shown in Figs. 3 and 4, are located during assembly of the roof structure immediately 35 below the various ribs 19, so that the edges of the clamping bars have bearing against the spanner sheets underlying the ribs 19.

To secure the ribs 19, spanner sheets 20 and clamping bars 22 in assembled relation or alternatively to hold the ribs 19, spanner sheets 21, and 40 clamping bars 22 in assembled relation, nutted bolts 24 are used, these nutted bolts passing through punched bolt receiving openings in the ribs 19 and clamping bars 22 and when spanner sheets 21 are used, these bolts also passing through 45 bolt openings formed in the sheets 21 at the time that the roof is being erected. The bolts 24 tightly clamp the parts together, preferably the heads of the bolts bearing against the ribs 19 and the nuts of the bolts being received within the 50 inverted V-shaped channels formed at the inner sides of the clamping bars 22, these channels preventing rotation of the nuts of the bolts as the bolts are tightened against their nuts.

To anchor and secure the roof to the top of the silo 14, straps 25 may be employed. These straps have their upper portions received within the channels at the lower ends of the ribs 19 and their upper portions are equipped with elongated slots 25a to receive the lowermost clamping bolts 24 55 therethrough, as well as to receive securing bolts 26 therethrough, and at the same time to permit of the projection of the straps 25 to greater or lesser distances below the lower ends of the ribs 19. Each strap 25 near its lower end is equipped 60 with a pair of openings to receive the shank and end portion of a hook 27 which engages the silo hoop 16. Nuts 28 mounted on the shanks of these hooks are used for drawing up the hooks against the hoop 16 to tightly secure the straps 25 to the 65 hoop and thereby form anchorage for the roof structure to the top of the silo. Of course, it will be understood that the straps 25 may be attached to the top of the silo in any other suitable manner. By provision of the slotted construction of the 70 straps 25, the bottom of the roof structure may be 75

properly leveled relative to the top of the silo conveniently.

In the form shown, the ring 23 is made adjustable to permit some variation in the circumference of the ring. The ring 23 is illustrated as being of 5 angular shape in cross section and it is formed from a single piece of metal having its ends connected by a nutted bolt 29. To permit of adjustment several bolt receiving openings 23a are provided adjacent the ends of the ring. 10

In place of using one of the spanner sheets 20 or 21 between the two ribs 19, adjacent the chute 15, a dormer 30 is employed, this dormer being best illustrated in Figs. 1 and 6. The lower part of the dormer 30 overlies the top portion of the 15 chute 15 and the edges of the dormer are equipped with outturned flanges 30a which are received within the channels of the ribs 19 and have the same functional purpose as do the flanges 20a of the spanner sheets 20. 20

The upper ends of the ribs 19, spanner sheets 20 and 21 and clamping bars 22 are secured to a horizontal flange of the ring 23 by means of nutted bolts 31. To close the opening formed by the ring 23 at the top of the silo roof, a hood 32 is provided. 25 This hood has a lower imperforate section 32a of truncated conical shape and attached to the lower imperforate section is an upper conical section 32b formed of "celloglass" which while shedding rain, permits light to penetrate into the silo as 30 through a window. The "celloglass" section 32b consists of screening treated with a cellulose product through which light may penetrate, the screening being formed in the shape of a cone. The hood 32 is removably secured to the ring 23 35 by means of angular brackets 33 attached to the inner side of the lower hood section 32a and having cam surfaces which engage projecting pins 34 carried by the ring 23. In other words, in applying the hood to the ring 23, the brackets 33 are 40 engaged below the pins 34 and the entire hood is then given a slight turn in a clockwise direction as viewed from the top of the silo, and the pins 34 riding upwardly on the cam surfaces of the brackets tightly draw the hood down in place on the top 45 of the silo roof.

In order to form a ladder for easy access to the top of the roof structure, a number of cross cleats 50 may be secured between a pair of adjacent ribs 19.

The channel formed in each rib 19 is of course considerably wider than the space occupied by the flange 20a of a spanner sheet 20, as best shown in Fig. 3, and in fact the spacing between the securing bolts 24 and the side flanges of the ribs 19 is 55 considerably greater than the thickness of a flange 20a of a spanner sheet 20. Accordingly, during the course of the erection of the roof and prior to the time that the nutted bolts 19 are tightened, 60 adjustment of the circumference of the roof is permitted within limits so as to adapt the roof to the top of a particular silo on which it is being erected. The spacing between adjacent ribs 19 65 can be varied within limits prior to the time that the bolts 24 are tightened, so as to give the roof somewhat greater or somewhat less circumference at its bottom. Thus if the silo is somewhat out of round, as is generally the case, or if the silo is of slightly larger or slightly smaller size at its upper 70 end than standard, the roof can be adjusted to fit the particular silo during erection of the roof without necessitating the use of ribs 19 and spanner sheets 20 of other than standard size. If it is 75 found, for example, that the circumference of the 80

5 top of the silo is slightly smaller than usual, several or any number of adjacent ribs 19 may be spaced center to center somewhat closer than usual by merely locating the flanges 20a of the spanner sheets 20 more closely to the bolts 24 at the time that the bolts 24 are tightened up. On the other hand if it is found necessary to increase the circumference of the roof somewhat beyond the normal circumference, this can readily be 10 done during the course of erection by merely locating the flanges 20a of several or a number of the spanner sheets 20 closely adjacent the side flanges of the ribs 19 that cooperate with these spanner sheets. This expandible and contractable feature of the present construction without necessitating change in the type or size of the various construction units used is one of the most important features of the present invention.

15 If it should be found that unusual expansion of the circumference of the bottom of the roof is required, beyond the limits permitted by use of the spanner sheets 20 alone in conjunction with the ribs 19, one or more of the spanner sheets 21 may be substituted for a like number of the spanner sheets 20. When a spanner sheet 21 is employed, wide adjustment between adjacent ribs is permitted inasmuch as the non-flanged portions of the spanner sheet 21 employed as best shown in Fig. 4, may overlap the next adjacent spanner sheet 20 or 21 to practically any desired extent.

20 It will be seen that the various building units we employ when assembled together as described, form an extremely light, strong, roof structure. 35 The channel-shaped ribs 19 give great strength and rigidity to the roof, while the bars 22 further strengthen the same. The side flanges 20a of the spanner sheets 20 and the side flanges 21a of the spanner sheets 21 give strength to the 40 various spanner sheets. The straps 25 permit the roof to be securely anchored to the top of the silo after the bottom of the roof has been properly leveled. The bolts 26 and the lowermost bolt 24 cooperating with the flanges 20a of the spanner sheets and the side flanges of the ribs 19 form effective barriers to prevent the entrance of birds to the silo through the lower ends of the channels of the ribs 19. The vertical flange of the ring 23 cooperating with the hood 32 effectively 45 prevents entry of the birds into the silo at the top thereof.

50 The channel-shaped ribs 19 afford a watershed between adjacent spanner sheets so as to effectively prevent the entrance of rain water to the silo. If there should be any leakage of water through the various bolt holes in the ribs 19, this water will drain into the upper channels of the bars 22 and drain out through the lower ends of these channels.

55 The hood 32 may be readily removed for filling the silo and the ring 23 forms a mouth of large diameter through which material may be fed into the silo. As there are no internal braces which occupy space within the roof structure, it is possible to utilize the roof as part of the silo itself so that the silo can be filled way up to the ring 23. The opening in the ring 23 is sufficiently large to permit a man to insert his body through the opening to tramp down silage stored within the roof structure. Of course the upper section 32b of the hood permits light to pass into the silo which is highly advantageous to workers within the silo.

60 Referring now to the form of the invention shown in Figs. 10, 11, 12 and 13, in Fig. 10 there

is illustrated a portion of a wall built from units 36, 37 and 38 of analogous construction to the units 19, 20 and 22 respectively, of the previously described construction. The rib 36 which in reality forms the stud of the wall shown in Fig. 10 is of exactly similar construction to the rib 19 previously described with the exception that rib 36 is straight instead of being of arcuate curvature. The spanner sheet 37 having side flanges 37a is similar to the spanner sheet 20 of the previously described construction with the exception that spanner sheet 37 is of uniform width throughout instead of being tapered. The clamping bar 38 is similar to the clamping bar 22 of the previously described construction with the exception that clamping bar 38 is straight instead of being curved. The units 36, 37 and 38 are interlocked and assembled in generally the same manner as are the parts 19, 20 and 22 of the previously described construction by nutted bolts 39 and the said units 36, 37 and 38 will form a straight wall instead of a curved wall. In horizontal cross section the wall shown in Fig. 10 will appear exactly as shown in Fig. 3. The benefits and advantages of the construction shown in Fig. 10 will be apparent from the discussion of the roof previously described.

25 It will be understood that the building units of the present invention can be assembled together to form roofs, closures, partition walls, building 30 walls and other building construction of many different types.

35 It will, of course, be understood that various changes may be made in the form, details, arrangement and proportions of the various parts 35 without departing from the scope of the present, invention, which, generally stated, consists in the matter shown and described and set forth in the appended claims.

40 What is claimed is:

1. A silo structure and the like comprising a plurality of ribs of channel-shape in cross section, means for anchoring the lower ends of said ribs in spaced relation, means for anchoring the upper ends of said ribs in spaced relation, a plurality 45 of spanner sheets extending between adjacent ribs, each spanner sheet having at least one side flange received within the channel of one of the ribs and said side flange being of such size relative to the channel as to permit positively limited lateral movement of the spanner sheet relative to the ribs as the building structure is being erected, and clamping means for securing said spanner sheets to said ribs to hold them against movement after erection.

50 2. A silo or similar building structure comprising a plurality of curved ribs of channel-shape in cross section, means for anchoring the lower ends of said ribs in spaced relation, means for anchoring the upper ends of said ribs in spaced relation, a plurality of curved spanner sheets extending between adjacent ribs, said spanner sheets having edge flanges received within the channels of the adjacent ribs and a plurality of 55 spaced clamping means securing the spanner sheets to said ribs, the channels of said ribs permitting positively limited variable spacing between the ribs as the building structure is erected prior to the application of said clamping means, said clamping means providing a rigid self-sustaining structure after erection.

60 3. A self-sustaining roof for silos and the like, comprising a plurality of curved ribs of channel-shape in cross section, means for anchoring the lower ends of said ribs to the top of a silo or the 65

like in such relation that the channels of said ribs are disposed inwardly, means for securing the upper ends of said ribs together in spaced relation, a plurality of curved spanner sheets, said sheets extending between adjacent ribs and having upturned edge flanges received within channels of adjacent ribs, the said channels being sufficiently wide to permit positively limited lateral shifting movement of said spanner sheets relative to said ribs as said roof is erected thereby permitting limited variance in the spacing between adjacent ribs and a plurality of spaced clamping means for clamping said spanner sheets and ribs rigidly together.

15 4. A roof for silos and the like, comprising a plurality of ribs of channel-shape in cross section having their lower ends disposed at spaced points on a curved arc and having their upper ends disposed at spaced points on a variable curved arc, 20 means for anchoring the lower ends of said ribs to the top of a silo or the like in the relation specified, means for securing together the upper ends of said ribs in the relation specified, spanner sheets extending between adjacent ribs, said 25 spanner sheets tapering from their lower ends upwardly, and having outturned side flanges received within the channels of adjacent ribs, the said channels being sufficiently wide to permit relative movement between said side flanges and 30 the ribs during erection and clamping means for tightly securing said spanner sheets and ribs together.

5. A self-supporting roof for silos and the like comprising a plurality of ribs of channel-shape in cross section, means for anchoring the lower ends of said ribs in spaced relation, means for connecting the upper ends of said ribs in spaced relation, spanner sheets extending between adjacent ribs, each spanner sheet having at least one 35 outturned side flange received within the channel of one of said ribs, said channels being of such size as to permit positively limited lateral movement of the flanges of said spanner sheets therein during the course of erection, clamping bars 40 underlying said ribs and spanner sheets, said clamping bars having edges adapted to engage said spanner sheets and a plurality of relatively closely spaced cooperating clamping elements extending between said ribs and said bars to hold the structure rigidly against movement after 45 erection.

6. A roof for silos and the like comprising a plurality of ribs of channel-shape in cross section, means for anchoring the lower ends of said ribs in circumferentially spaced relation, a ring connected to the upper ends of said ribs, spanner sheets extending between adjacent ribs, each spanner sheet having at least one outturned side flange received within the channel of one of said 50 ribs, said channels being of such size as to permit limited lateral adjusting movement of the flanges of the spanner sheets therein during the course of erection, clamping means securing said spanner sheets and ribs together to prevent movement after erection, said ring forming an opening at the top of the roof and a hood removably closing said opening.

7. A roof for silos and the like comprising a plurality of ribs of channel-shape in cross section, straps connected to the lower ends of said ribs for adjustable extension therefrom, means for securing said straps to the upper part of a silo, spanner sheets extending between adjacent ribs, each spanner sheet having at least one outturned side flange received within the channel of

one of the ribs, said channels being of such size as to permit limited lateral movement of the flanges of the spanner sheets therein during the course of erection and means for clamping said ribs and spanner sheets together.

8. The structure defined in claim 6, said ring being adjustable in circumferential size.

9. A silo roof of dome form comprising a supporting frame of dome-like structure made up of a plurality of curved ribs having their lower ends arranged at circumferentially spaced intervals around a circle, said ribs being preformed to a predetermined curvature, the adjacent ribs gradually converging toward their upper ends, a covering for said frame, said covering being composed of a plurality of sections adapted to form segments of the dome, said sections being formed of flat sheets and means for securing the sheets to the frame so that the sheets will assume the curvature of the ribs of the frame, the edges of adjacent sheets being free from each other, said means permitting limited transverse movement of the sheets relative to the frame and to each other.

10. A silo roof of dome form comprising a supporting frame of dome-like structure made up of a plurality of curved ribs having their lower ends arranged at circumferentially spaced intervals around a circle, said ribs being preformed to a predetermined curvature, the adjacent ribs gradually converging towards their upper ends, a covering for said frame, said covering being composed of a plurality of sheet metal sections adapted to form segments of the dome, said sections being formed by flat sheets, and means for securing the sheets to the frame so that the sheets will assume the curvature of the ribs of the frame, the edges of the adjacent sheets being free from each other.

11. A silo roof of dome form comprising a supporting frame of dome-like structure, a covering for said frame, said covering being composed of a plurality of sheet metal sections adapted to form segments of the dome, said segments being formed of flat sheets, and means for securing the sheets to the frame in such a manner that the sheets will assume the curvature of the frame, the edges of adjacent sheets being non-interlocking.

12. A silo roof comprising a supporting frame made up of a plurality of curved ribs arranged to form a dome-like structure, a covering for said frame, said covering being composed of a plurality of segmental sections, each of said sections being made of a flat sheet, said sheets being secured to said frame in such a manner that the edges of the sheets will overlap each other and the sheets will assume the curvature of the ribs of the frame.

13. A self-sustaining roof for silos and the like, comprising a plurality of ribs of channel-shape in cross section, having their lower ends disposed at spaced points on a curved arc, and having their upper ends disposed at spaced points on a curved arc, means for anchoring the lower ends of said ribs to the top of a silo or the like in the relation specified, means for securing together the upper ends of said ribs in the relation specified, spanner sheets extending between adjacent ribs, said spanner sheets tapering from their lower ends upwardly, each spanner sheet having at least one side flange received within a channel of an adjacent rib, the said channels being sufficiently wide to permit relative movement between a side flange received therein and the rib during erection, and

clamping means for tightly securing said spanner sheets and ribs together.

14. A self-sustaining roof for silos and the like comprising a plurality of ribs of channel-shape in cross section, having their lower ends disposed at spaced points on a curved arc and having their upper ends disposed at spaced points on a curved arc, means for anchoring the lower ends of said ribs to the top of a silo or the like in the relation specified, means for securing together the upper ends of said ribs in the relation specified, spanner

sheets extending between adjacent ribs, said spanner sheets tapering from their lower ends upwardly, at least certain of said spanner sheets having side portions overlapping side portions of adjacent spanner sheets to permit of relative movement between adjacent overlapping sheets and clamping means for tightly securing said spanner sheets and ribs together. 5
